ABSTRACT

The disclosure generally relates to a locating assembly as a component of a locating table segment for positioning truss segments in a truss assembly system. The system generally includes a plurality of table segments aligned in parallel and adapted to position a series of locating blocks on a top surface of the system/table, where each block is a component of one of a plurality of locating assemblies in the system. The block positions collectively define an outer boundary of a support truss (e.g., as a roofing truss). Once the blocks are moved to their desired position, appropriately sized truss segments are placed within the block-defined boundary and fastened together.

APPARATUS AND METHODS FOR TRUSS ASSEMBLY

CROSS-REFERENCE TO RELATED APPLICATION

This application claims the benefit of U.S. Provisional Patent Application No. 61/464,012, filed Feb. 25, 2011, the disclosure of which is incorporated herein by reference in its entirety.

BACKGROUND OF THE DISCLOSURE

1. Field of the Disclosure

The disclosure generally relates to apparatus, systems, and methods for assembling a building truss such as a roofing truss. A system including one or more locating table segments and one or more locating assemblies defining an assembly table with moveable locating assemblies or blocks is disclosed.

2. Brief Description of Related Technology

Tables and related systems with adjustable stops for assembling building trusses are known. Such systems often have one or more drawbacks, for example including excessively noisy operation and/or unreliable operation (e.g., resulting from the use of a conventional threaded rod drive system to position the stops at desired locations) as well as a susceptibility to interference and/or malfunctions from construction debris during normal operational use.

Objects

While the related art discloses truss assembly systems, there still exists a need for an improved truss assembly system along with its related components in order to provide quieter, more reliable operation under normal working conditions.

Therefore, it is an object of the present disclosure to provide an improved truss assembly system having improved operational characteristics. This and other objects will become increasingly apparent by reference to the following description.

SUMMARY

The disclosure relates to a locating assembly for use in a truss assembly system. The locating assembly comprises: (a) a mounting block having a top surface and defining: (i) a longitudinal direction, (ii) a width direction perpendicular to the longitudinal direction, and (iii) a height direction perpendicular to the longitudinal direction and the width direction; (b) a guide assembly having a bottom surface and an opposing top surface, the guide assembly bottom surface being mounted to the mounting block top surface and extending in the height direction relative to the mounting block, the guide assembly comprising: (i) a first portion having a first width, (ii) a second portion having a second width, and (iii) a third portion having a third width, wherein (A) the first portion is located closer in the height direction to the mounting block top surface than second portion and the third portion, (B) the second portion is located intermediate the first portion and the third portion in the height direction, and (C) the first width and the third width are greater than the second width; (c) optionally a locating block having a bottom surface, the locating block bottom surface being mounted to the guide assembly top surface and extending in the height direction relative to the guide assembly; and (d) optionally (i) a fastening means for fastening the mounting block, the guide assembly, and optionally the locating block together, and (ii) a compression

means for exerting a compression force in the height direction between the first portion and the third portion of the guide assembly.

Various refinements of the locating assembly are possible.

- 5 For example, in an embodiment, the mounting block and/or the locating block comprise a metal material (e.g., steel). The mounting block can have an elongate shape extending in the longitudinal direction and optionally a rectangular cross section in the width and height directions. The guide assembly
- 10 can comprise a material having a low coefficient of static friction when in contact with steel and/or can comprise a low-friction polymeric material selected from the group of poly(amides), poly(imides), poly(alkylenes), fluorinated poly(alkylenes), poly(vinyl aromatics), poly(acetals),
- 15 copolymers thereof, and mixtures thereof. The guide assembly suitably has an I-shaped cross-section in the width direction and the height direction, and the third portion of the guide assembly can have a circular cross section in the width direction and the longitudinal direction. Suitably, the guide assembly comprises two or more separate portions mounted together (e.g., (i) the first portion and the second portion are integrally formed, and (ii) the third portion is a separate structure from the first portion and the second portion; (i) the second portion and the third portion are integrally formed,
- 20 and (ii) the first portion is a separate structure from the second portion and the third portion; the first portion, the second portion, and the third portion are separately formed; or (i) the first portion and a part of the second portion are integrally formed, and (ii) the third portion and a remaining part of the
- 25 second portion are integrally formed). The locating block can have a circular cross section in the width direction and the longitudinal direction. The fastening means and the compression means can collectively comprise a bolt extending in the height direction through the mounting block, the guide assembly, and optionally the locating block. In an embodiment, the mounting block and the guide assembly are separately formed structures. In another embodiment, the mounting block and at least a portion of the guide assembly form an integral structure.
- 30
- 35
- 40 In another refinement of the locating assembly, (i) the mounting block extends in the longitudinal direction; and (ii) the locating assembly further comprises an alignment guide having a bottom surface and an opposing top surface, the alignment guide bottom surface being mounted to the mounting block top surface at a longitudinal position spaced away from the guide assembly and extending in the height direction relative to the mounting block, the alignment guide comprising: (A) a first portion having a first width, and (B) a second portion having a second width, wherein (I) the first portion is located closer in the height direction to the mounting block top surface than second portion, and (II) the first width is greater than the second width.
- 45
- 50
- 55 The disclosure also relates to a locating table segment also for use in a truss assembly system. The locating table segment comprises: (a) a table segment having (i) a top surface, (ii) an opposing bottom surface and (iii) a side surface intermediate the top surface and the bottom surface, and defining (i) a longitudinal direction, (ii) a width direction perpendicular to the longitudinal direction, and (iii) a height direction perpendicular to the longitudinal direction and the width direction;
- 60 (b) the locating assembly in any of its various embodiments positioned adjacent the table segment side surface, wherein: (i) the longitudinal direction of the locating assembly mounting block and the longitudinal direction of the table segment are substantially parallel; (ii) the first portion of the guide assembly is below the table segment bottom surface; (iii) the second portion of the guide assembly is adjacent the table
- 65

segment side surface; (iv) the third portion of the guide assembly is above the table segment top surface; (v) the mounting block is below the table segment bottom surface; and (vi) the locating block, when present, is located above the table segment top surface; and (c) a movement means for moving the locating assembly in the longitudinal direction, wherein (i) the movement means is mounted to the locating assembly, and (ii) the movement means is positioned below the table segment bottom surface.

Various refinements of the locating table segment are possible. For example, in an embodiment, the table segment comprises a metal material (e.g., steel). The table segment can have an elongate shape extending in the longitudinal direction and optionally a rectangular cross section in the width and height directions. The first portion and the third portion of the locating assembly guide assembly can maintain the locating assembly in a fixed position in the height direction relative to the table segment, for example where the first portion and the third portion exert a compressive force between the top surface and the bottom surface of the table segment. The movement means can comprise: (i) a longitudinal translation means for moving the locating assembly in the longitudinal direction, the longitudinal translation means being mounted to the mounting block of the locating assembly and extending between proximal and distal ends of the table segment; and (ii) a driver means operatively coupled to the longitudinal translation means for moving the longitudinal translation means and the locating assembly in the longitudinal direction. In a refinement, (i) the driver means comprises (A) a motor mounted to the table segment bottom surface, and (B) a sprocket rotationally driven by and operatively coupled to the motor; and/or (ii) the longitudinal translation means comprises an endless chain extending between the proximal and distal ends of the table and being operatively connected to the rotationally driven sprocket. In an embodiment, the locating table segment has a single locating assembly and a single movement means mounted thereto. In an alternative embodiment, the locating table segment has (i) a first locating assembly and a first movement means mounted thereto, with the first locating assembly being positioned adjacent a first side surface of the table segment, and (ii) a second locating assembly and a second movement means mounted thereto, with the second locating assembly being positioned adjacent a second side surface of the table segment, the second side surface opposing the first side surface.

The disclosure also relates to a truss assembly system comprising: (a) a first table segment comprising the locating table segment according to any of its various embodiments; (b) a second table segment having (i) a top surface, (ii) an opposing bottom surface and (iii) a side surface intermediate the top surface and the bottom surface, and defining (i) a longitudinal direction, (ii) a width direction perpendicular to the longitudinal direction, and (iii) a height direction perpendicular to the longitudinal direction and the width direction; wherein: (i) the longitudinal direction of the locating assembly mounting block, the first table segment, and the second table segment are substantially parallel, (ii) the first table segment and the second table segment are spaced apart to define a slot between adjacent side surfaces thereof, the slot having a shape and cross section complementary to that of the second portion of the locating assembly guide assembly; (iii) the first portion of the guide assembly is below the first and second table segment bottom surfaces; (iv) the second portion of the guide assembly is disposed in the slot and adjacent the first and second table segment side surfaces; (v) the third portion of the guide assembly is above the first and second table segment top surfaces; (vi) the mounting block is below

the first and second table segment bottom surfaces and the first portion of the guide assembly; and (vii) the locating block, when present, is located above the first and second table segment top surfaces.

Various refinements of the truss assembly system are possible. For example, in an embodiment, the system comprises a plurality of first and second table segments positioned adjacent each other (e.g., where both are mono-locating table segments or where dual-locating table segments alternate with blank table segments), thereby defining a table surface comprising a plurality of slots each having an independently positionable locating assembly therein. The system can comprise a computer control system operatively connected to the plurality of movement means for independently selecting the longitudinal position of each locating assembly.

The disclosure also relates to a method for assembling a truss. The method comprises: (a) providing the truss assembly system according to any of its various disclosed embodiments; (b) positioning each of the locating assemblies to correspond to a shape of a construction truss; (c) positioning (i) a plurality of truss segments on the table surface in the shape defined in (b), and (ii) optionally one or more interior truss support segments within the interior of the shape defined in (b); and (d) fastening the plurality of truss segments and any truss support segments together to form an assembled truss.

All patents, patent applications, government publications, government regulations, and literature references cited in this specification are hereby incorporated herein by reference in their entirety. In case of conflict, the present description, including definitions, will control.

Additional features of the disclosure may become apparent to those skilled in the art from a review of the following detailed description, taken in conjunction with the examples, drawings, and appended claims, with the understanding that the disclosure is intended to be illustrative, and is not intended to limit the claims to the specific embodiments described and illustrated herein.

BRIEF DESCRIPTION OF THE DRAWINGS

For a more complete understanding of the disclosure, reference should be made to the following detailed description and accompanying drawings wherein:

FIG. 1 is a top view of a truss assembly system including a locating assembly and a locating table segment according to the disclosure.

FIG. 2 is a side view of a locating assembly according to the disclosure.

FIG. 3 is a top view of the locating assembly in FIG. 2.

FIG. 4 is a bottom view of the locating assembly in FIG. 2.

FIGS. 5A-5D are front views of the locating assembly and guide assembly according to various embodiments of the disclosure.

FIGS. 6A-6E are views of the locating assembly components (A: mounting block, B: first and second portions of guide assembly, C: third portion of guide assembly, D: locating block, E: alignment guide).

FIG. 7 is an exploded perspective view of a locating table segment according to the disclosure.

FIG. 8 is a bottom perspective view of a locating table segment according to the disclosure.

While the disclosed apparatus and methods are susceptible of embodiments in various forms, specific embodiments of the disclosure are illustrated in the drawings (and will hereafter be described) with the understanding that the disclosure

is intended to be illustrative, and is not intended to limit the claims to the specific embodiments described and illustrated herein.

DETAILED DESCRIPTION

With reference to FIGS. 1-8, the present disclosure generally relates to a locating assembly 100 as a component of a locating table segment 310 for positioning truss segments 410 in a truss assembly system 300. The system 300 generally includes a plurality of table segments 200 aligned in parallel and adapted to position a series of locating blocks 160 on a top surface 340 of the system/table 300, where each block 160 is a component of one of a plurality of locating assemblies 100 in the system 300. The block 160 positions collectively define an outer boundary of a support truss 400 (e.g., as a roofing truss). Once the blocks 160 are moved to their desired positions, appropriately sized truss segments 410 (e.g., wooden boards) are placed within the block-defined boundary and fastened together (e.g., via screws, nails, or any other fastening means 412; with or without internal webbing truss support segments 420).

The apparatus of the present disclosure have several advantages over related automated truss jig setting systems. The locating assembly 100 includes at least one guide that ensures the positional stability of the locating block 160 (i.e., in terms of its relative position in all three coordinate directions) as the locating assembly 100 is moved along the length of its table segment 200/310. Suitably, the guide portions of the locating assembly 100 are formed from low-friction materials that both (i) reduce noise associated with the movement of the locating assembly 100 and (ii) reduce the power needed to drive the locating assembly 100 during use. In some embodiments, the locating assembly 100 is incorporated into the locating table segment 310/truss assembly system 300 with an endless chain and driven sprocket that move the locating assembly 100 in both longitudinal directions along the table segment 200. The chain-and-sprocket assembly provides a reliable means to repeatedly position a given locating assembly 100 at any precisely selected longitudinal position with very little noise. Additionally, the construction of the locating assembly 100 and its incorporation into the locating table segment 310 limit the ability of construction debris to fall below the table surface 340 or otherwise interfere with the operation/movement of the locating assembly 100.

As used herein, the term "mounted" can represent a direct mounting between two structural units, where the indicated parts/units are in direct contact with each other. Alternatively or additionally, the term can represent an indirect mounting between two structural units, where the indicated parts/units are connected via an intervening structure. Generally, the relative positions of two units mounted together are at least partially if not completely constrained (e.g., two parts mounted together may be fixed in position relative to each other, or they may be mounted in a way to permit rotational or translational motion relative to each other).

As used herein, the terms "above," "below," "top," and "bottom" are relative spatial indicators for the indicated structural elements. The terms "above" and "top" can be used to represent relative spatial positioning in a relevant height direction for a first element having a height coordinate higher than that of a second element denoted with the term "below" or "bottom."

Locating Assembly

FIGS. 2-5 illustrate the locating assembly 100 in various embodiments according to the disclosure. The locating assembly 100 generally includes a mounting block 120 (e.g.,

for mounting of the assembly 100 to a movement means 240 of a locating table segment 310/truss positioning system 300), a guide assembly 140 mounted to the top of the mounting block 120, and (optionally) a locating block 160 mounted to the top of the guide assembly 140.

The illustrated mounting block 120 includes a top surface 122, an opposing bottom surface 124, and opposing side surfaces 126 extending between a proximal end 128 and a distal end 130 of the block 120. The structure of the block 120 generally defines a longitudinal direction L_M , which is the direction of extent between the proximal and distal ends 128, 130. The longitudinal direction L_M can be defined, for example, as the centerline/length axis of the block 120 and/or the direction of travel of the block 120/locating assembly 100 during use in the locating table segment 310. Similarly, the block 120 also defines a width direction W_M that is perpendicular to the longitudinal direction L_M and generally corresponds to the direction of extent between the side surfaces 126. The block 120 further defines a height direction H_M that is perpendicular to both the longitudinal direction L_M and the width direction W_M and generally corresponds to the direction of extent between the top and bottom surfaces 122, 124.

As illustrated, the mounting block 120 can have an elongate shape extending in the longitudinal direction L_M (e.g., generally straight) and a rectangular cross section in the width W_M and height H_M directions. The block 120 suitably has a flat top surface 122 to facilitate the mounting of other components thereupon, but any shape is possible for the top 122 and other surfaces of the block 120. The block 120 (as well as other apparatus and system components) is generally suitably sized for a truss assembly operation, in which case the width and height of the block 120 can be at least 0.5 cm, 1 cm, or 2 cm and/or up to 2 cm, 5 cm, or 10 cm, and the length of the block 120 can be at least 1 cm, 2 cm or 5 cm and/or up to 5 cm, 10 cm, 20 cm or 50 cm. As further shown, the block 120 can include a first receiving hole 132 at/near its proximal end 128 for mounting a guide assembly 140 (described below) and a second receiving hole 134 at/near its distal end 130 for mounting an alignment guide 180 (also described below), where the holes 132, 134 can extend partially or completely through the block 120 in the height direction H_M .

The mounting block 120 can be formed from any suitable rigid, resilient material such as a metal material (e.g., having a steel construction) or a rigid plastic material.

The illustrated guide assembly 140 includes a top surface 142, an opposing bottom surface 144 (e.g., opposing in the height direction H_M), and opposing side surfaces 146 (e.g., opposing in the width direction W_M). The bottom surface 144 of the guide assembly 140 is mounted to the top surface 122 of the mounting block 120 (e.g., via a receiving hole 156 extending therethrough that is complementary to the first receiving hole 132 of the block 120) so that the guide assembly 140 extends upwardly in the height direction H_M relative to the block 120 (e.g., away therefrom). The guide assembly 140 includes at least three portions, which can form a single integral structure for the guide assembly 140, but which suitably include two or more separate structures that are mounted together to form a composite guide assembly 140 structure that is incorporated into the locating assembly 100. More specifically, the guide assembly 140 includes (i) a first portion 148 having a first width W_1 , (ii) a second portion 150 having a second width W_2 , and (iii) a third portion 152 having a third width W_3 . As shown, the first, second, and third portions 148, 150, and 152 are oriented at successively further height positions away from the mounting block 120 (e.g., the first portion 148 is located closer in the height direction H_M to the mounting block 120 top surface 120 than the second portion 150 and

the third portion 152, and the second portion 150 is located intermediate the first portion 148 and the third portion 152 in the height direction H_M . The various width, height, length, and diameter (when applicable) values of the guide assembly 140 and/or its component portions can be at least 0.2 cm, 0.5 cm, 1 cm, or 2 cm and/or up to 1 cm, 2 cm, 5 cm, or 10 cm.

The guide assembly 140 provides a means to stabilize the vertical position of the locating assembly 100 relative to adjacent table segments 200 when integrated into a locating table segment 310 or truss positioning system 300. In particular, the first width W_1 and the third width W_3 can be greater than the second width W_2 (e.g., where the first width W_1 and the third width W_3 can be the same or different), thereby defining two receiving portions 158 for table segment 200 sides/edges at opposing side surfaces 146 of the guide assembly 140 (e.g., in which case table segment 200 sides/edges in the receiving portions are constrained against vertical motion in either direction). The portions of the guide assembly 140 are illustrated as having constant/uniform widths (or diameters, in the case of cylindrical components). However, the portions can have non-uniform widths (e.g., widths varying as a function of the height direction H_M). In such cases, the guide assembly 140 can be shaped such that the first width W_1 at a selected height position in the first portion 148 and the third width W_3 at a selected height position in the third portion 152 are greater than the second width W_2 at a selected height position in the second portion 150 (e.g., at least some parts of the first and third portions are wider than at least some part of the second portion).

As generally shown in the figures, the guide assembly 140 can have an I-shaped cross-section in the width direction W_M and the height direction H_M . Such a shape conveniently defines rectangular receiving portions 158 complementary to a rectangularly shaped table segment 200. The first and second portions 148, 150 suitably have a constant cross sectional shape extending in the longitudinal direction L_M . This can provide a means to stabilize the horizontal position of the locating assembly 100 relative to adjacent table segments 200 when integrated into a locating table segment 310 or truss positioning system 300 insofar as the side surfaces 146 of the second portion 150 are generally adjacent to and/or in contact with neighboring edges/sides 206 of adjacent table segments 200. In an embodiment, the third portion 152 of the guide assembly 140 has a circular cross section in the width direction W_M and the longitudinal direction L_M (e.g., perpendicular to the height direction H_M), with the diameter of the circular cross section corresponding to the third width W_3 . In other embodiments, the third portion 152 can more generally have any other curved, non-straight edges that facilitate the positioning of a straight/flat truss segment 410 edge at a variety of different angles relative to the third portion 152.

FIGS. 5A-5D illustrate various embodiments in which the guide assembly 140 includes two separate structural elements or portions combined or mounted together in a composite assembly 140 structure (e.g., with a composite I-shaped cross-section as described above). FIG. 5A illustrates an embodiment in which (i) the first portion 148 and the second portion 150 are integrally formed (e.g., in a T-shaped rectangular block having a T-shaped cross section in the width direction W_M and the height direction H_M , and extending in the longitudinal direction L_M), and (ii) the third portion 152 is a separate structure from the first portion 148 and the second portion 150 (e.g., having a cylindrical shape, such as a disc-shaped spacer/washer 154). FIG. 5B illustrates an embodiment in which (i) the second portion 150 and the third portion 152 are integrally formed (e.g., a block having an inverted T-shaped cross section in the width direction W_M and the

height direction H_M , and extending in the longitudinal direction L_M , where the third portion 152 can have a cylindrical shape as above the second portion 150 can have a rectangular block shape), and (ii) the first portion 148 is a separate structure from the second portion 150 and the third portion 152 (e.g., having a generally flat, rectangular plate shape). FIG. 5C illustrates an embodiment in which (i) the first portion 148 and a part of the second portion 150 are integrally formed, and (ii) the third portion 152 and a remaining part of the second portion 150 are integrally formed (e.g., shapes with two complementary T-shaped cross sections to form a composite I-shaped cross section, such as a cylindrical shape (third portion 152) and rectangular block shapes (first and second portions 148, 150)). FIG. 5D illustrates an embodiment in which the first portion 148, the second portion 150, and the third portion 152 are separately formed (e.g., each having the rectangular or cylindrical shapes as above).

The guide assembly 140 (e.g., whether integrally formed or including separate structural components) is suitably formed from a low-friction material (i) to reduce the force required to traverse the locating assembly 100 along the length of a table segment 200, (ii) to reduce the wear on other (e.g., metal or steel) components of the locating table segment 310/truss positioning system 300, and (iii) to reduce the noise generated by the locating assembly 100 in use. Such materials can be characterized as having a low coefficient of friction (e.g., static or dynamic), for example when in contact with other like materials or with a metal (e.g., steel, which is a common material for other system 300 components). Suitable values for the coefficient of friction can include values less than that of a comparable steel-steel system (e.g., about 0.7-0.8 (static) or about 0.4-0.7 (dynamic)), for example not more than 0.6, 0.4, 0.2, 0.1, 0.07, or 0.05, and/or at least 0.01, 0.02, 0.04, 0.06, 0.08, or 0.1 (e.g., where such values can represent static or dynamic friction coefficients, with dynamic friction coefficients generally being equal to or less than their static counterparts). Suitable low-friction materials can include various plastic or polymeric materials such as poly(amides) (e.g., aliphatic polyamides including nylons such as nylon 6, nylon 6,6), poly(imides), poly(alkylenes) (e.g., polyethylene, polypropylene), fluorinated poly(alkylenes) (e.g., perfluorinated poly(alkylenes) such as poly(tetrafluoroethylene), poly(vinyl aromatics) (e.g., polystyrene), poly(acetals) (e.g., polyoxymethylene). Copolymers including one or monomers of the foregoing polymers (e.g., along with an additional monomer, whether or not in the foregoing list) also can be used. Similarly, mixtures of various low-friction polymeric materials can be used. In some embodiments, the low-friction material can further include one or more filler components, for example those that further reduce the frictional coefficient of the material such as a solid lubricant like graphite and/or molybdenum disulfide.

The locating assembly 100 can further include a locating block 160. The block 160 includes a top surface 162, an opposing bottom surface 164 (e.g., opposing in the height direction H_M), and a side surface 166. The bottom surface 164 of the block 160 is mounted to the top surface 142 of the guide assembly 140 (e.g., via a receiving hole 168 extending therethrough that is complementary to the receiving hole 156 of the guide assembly 140 and the first receiving hole 132 of the block 120) so that the block 160 extends upwardly in the height direction H_M relative to the block 120 and the guide assembly 140 (e.g., away therefrom). Similar to the third portion 152, the block 160 can have a generally cylindrical shape with a circular cross section in the width direction W_M and the longitudinal direction L_M (e.g., perpendicular to the height direction H_M), with the diameter of the circular cross

section suitably being at least as large as the third width W_3 (or the equivalent diameter for a circular third portion 152 and generally larger than the width of a slot 330 defined by adjacent table segments 200). Similar to the third portion 152, the block 160 can more generally have any other curved, non-straight edges that facilitate the positioning of a straight/flat truss segment 410 edge at a variety of different angles relative to the side surface 166 of the block 160. Similar to the mounting block 120, the locating block 160 can be formed from any suitable rigid, resilient material such as a metal material (e.g., having a steel construction) or a rigid plastic material. In an embodiment, the block 160 can be omitted, in which case the third portion 152 suitably can be extended in the height direction H_M so that the third portion 152 can serve as both the locating block and the upper portion of the guide assembly 140. The various width, height, length, and diameter (when applicable) values of the locating block 160 can be at least 0.5 cm, 1 cm, or 2 cm and/or up to 2 cm, 5 cm, or 10 cm.

The locating assembly 100 can include (i) a fastening means for fastening the mounting block 120, the guide assembly 140 (e.g., including components thereof), and the locating block 160 (when present) together, and (ii) a compression means for exerting a compression force F in the height direction H_M between the first portion 148 and the third portion 152 of the guide assembly 140 (e.g., illustrated as two opposing compression forces F in FIG. 5A). The fastening means and the compression means can be collectively represented as element 170, for example as a bolt or rod 172 (e.g., metal, steel) extending in the height direction H_M through the mounting block 120, the guide assembly 140, and the locating block 160. The bolt or rod 172 can be threaded and extend through complementary receiving holes 132, 156, 168 in the fastened components, such as where the mounting block 120 has a threaded cylindrical receiving hole 132 to receive the threaded distal end of the bolt 172, where tightening of the bolt 172 at its proximal end (e.g., at the locating block 160) fastens the components together and induces the compression force F .

The locating assembly 100 can include an alignment guide 180, for example when the mounting block 120 extends in the longitudinal direction L_M and provides additional mounting area for the guide 180 (e.g., which is separate and spaced apart from the guide assembly 140). The alignment guide 180 and guide assembly 140 are similar in structure, size, and construction (e.g., formed from similar low-friction materials). The illustrated alignment guide 180 includes a top surface 182, an opposing bottom surface 184 (e.g., opposing in the height direction H_M), and opposing side surfaces 186 (e.g., opposing in the width direction W_M). The bottom surface 182 of alignment guide 180 is mounted to the top surface 122 of the mounting block 120 (e.g., via a receiving hole 192 extending therethrough that is complementary to the second receiving hole 134 of the block 120) so that the alignment guide 180 extends upwardly in the height direction H_M relative to the block 120 (e.g., away therefrom). Analogous to the guide assembly 140, the alignment guide 180 can include two or more portions, which can form a single integral structure for the alignment guide 180. More specifically, the alignment guide 180 includes (i) a first portion 188 having a first width W_1 and (ii) a second portion 190 having a second width W_2 . As shown, the first and second portions 188, 190 are oriented at successively further height positions away from the mounting block 120 (e.g., the first portion 188 is located closer in the height direction H_M to the mounting block 120 top surface 120 than the second portion 190).

The alignment guide 180 can partially stabilize the vertical position of the locating assembly 100 relative to adjacent

table segments 200 when integrated into a locating table segment 310 or truss positioning system 300. In an embodiment, the first width W_1 can be greater than the second width W_2 , thereby defining two extending lip or flange portions at 5 opposing side surfaces 186 of the alignment guide 180 (e.g., in which case the lip or flange portions against table segment 200 sides/edges constrain the locating assembly 100 against upward vertical motion). Various suitable shapes for the first and second portions 188, 190 alignment guide 180 are analogous to the first and second portions 148, 150 of the guide assembly 140, as described above. In an embodiment, the height of the alignment guide 180 is the same or less than the height of the corresponding first and second portions 148, 150 of the guide assembly 140 such that the top surface 182 of the alignment guide 180 generally lies at or below the top surface 202 (or table surface 340) in an assembled apparatus. In another embodiment, alignment guide 180 can be shaped without any particular constraint on the first width W_1 and the second width W_2 , such as when the two widths are the same 10 and the alignment guide 180 can have a simple rectangular block structure. Further similar to the guide assembly 140, the first and second portions 188, 190 suitably have a constant cross sectional shape extending in the longitudinal direction L_M . This can provide a further means to stabilize the horizontal position of the locating assembly 100 relative to adjacent table segments 200 when integrated into a locating table segment 310 or truss positioning system 300 insofar as the side surfaces 186 of the second portion 190 are generally adjacent to and/or in contact with neighboring edges/sides 15 20 25 30 35 40 45 50 55 60 65 70 75 80 85 11

206. The table segment 200 further defines a height direction H_T that is perpendicular to both the longitudinal direction L_T and the width direction W_T , and generally corresponds to the direction of extent between the top and bottom surfaces 202, 204.

As illustrated, the table segment 200 can have an elongate shape extending in the longitudinal direction L_T (e.g., generally straight) and further can have a rectangular cross section in the width W_T and height H_T directions. The length of table segment 200 can be at least 1 m, 2 m, or 3 cm and/or up to 6 m, 8 m, or 10 m. The height of table segment 200 can be at least 0.5 cm, 1 cm, or 2 cm and/or up to 2 cm, 5 cm, or 10 cm. The width of table segment 200 can be at least 2 cm, 5 cm, 10 cm, or 15 cm and/or up to 20 cm, 25 cm, 30 cm, 40 cm, or 50 cm. The table segment 200 suitably has a flat top surface 202 to facilitate the placement of truss segments 410 of a flat table surface 340 defined by the collective top surfaces 202, but any desired shape may be for the other surfaces of the table segment. For example, the side surfaces 206 are illustrated as being generally vertical or perpendicular to the top surface 202, but either or both of the side surfaces 206 may angled (i.e., not perpendicular) relative to the top surface 202 such that a cross section between the side surfaces 206 of adjacent table segments 200 (e.g., the slot 330) can have a non-rectangular shape (e.g., a generally trapezoidal shape that expands upwardly or downwardly).

Similar to the mounting block 120, the table segment 200 can be formed from any suitable rigid, resilient material such as a metal material (e.g., having a steel construction) or a rigid plastic material.

The locating table segment 310 includes the locating assembly 100 (according to any of its various embodiments) positioned adjacent the side surface 206 of the table segment 200 (e.g., extending away from the side surface 206 in the width direction W_T). The locating assembly 100 is positioned such that the longitudinal direction L_M of the mounting block 120 and the longitudinal direction L_T of the table segment 200 are substantially parallel (e.g., parallel or parallel to within a machining tolerance such as not more 1°, 0.5°, 0.2°, or 0.1°). In the assembled locating table segment 310, a portion of a table segment 200 side/edge is located within either or both of the two receiving portions 158 defined by the guide assembly 140.

More specifically, the first portion 148 of the guide assembly 140 is below the table segment 200 bottom surface 204, for example where a segment such as a lip or flange section of the first portion 148 extends below the table segment 200 and can be in contact with or next to the bottom surface 204, with or without any intervening structure. Similarly, the third portion 152 of the guide assembly 140 is above the table segment 200 top surface 202, for example where a segment such as a lip or flange section of the third portion 152 extends above the table segment 200 and can be in contact with or next to the top surface 202, with or without any intervening structure. The second portion 150 of the guide assembly 140 is adjacent the table segment 200 side surface 206, for example where all or some the side surface 146 of the guide assembly second portion 150 is in contact with or next to the side surface 206, with or without any intervening structure. Accordingly, as illustrated, the mounting block 120 is below both the table segment 200 bottom surface 204 and the first portion 148 of the guide assembly 140, and the locating block 160 is located above the table segment 200 top surface 202 and the third portion 152 of the guide assembly 140.

As shown, the first portion 148 and the third portion 152 of the guide assembly 140 maintain the locating assembly 100 in a fixed position in the height direction H_M (or H_T as all three

12

coordinate directions are generally parallel or substantially parallel in many embodiments) relative to the table segment 200. In particular, the first portion 148 and the third portion 152 exert a compressive force F between the top surface 202 and the bottom surface 204 of the table segment 200 (e.g., on the edge portion of the top and bottom surfaces 202, 204 near the side surface 206) such as when the compression/fastening means 170 drives/pushes the first portion 148 upward and the third portion 152 downward the height direction H_M .

10 The movement means 240 moves the locating assembly 100 in the longitudinal direction L_M or L_T of either or both of the mounting block 120 and the table segment 200. The movement means 240 is mounted to the locating assembly 100 in any convenient fashion, for example via a connector 242 portion of the mounting block 120 (e.g., extending laterally outward as shown in FIGS. 4 and 6A, such as via a weld between a metal/steel connector 242 and chain 252), which is in turn mounted to the movement means 240 (e.g., the longitudinal translation means 250 in general or the chain 252 as shown in the figures). As shown in the figures, the movement means 240 is suitably mounted to the table segment 200 (e.g., to the bottom surface 204 thereof), but the movement means 240 can be more generally positioned below the table segment 200 bottom surface 204 without being mounted thereto (e.g., the movement means 240 can be mounted to other support structure (not shown) as long as the locating assembly 100 is positioned appropriately relative to the table segment 200).

30 The movement means 240 generally includes a longitudinal translation means 250 for moving the locating assembly 100 in the longitudinal direction L_M or L_T . The longitudinal translation means 240 is mounted to the mounting block 120 of the locating assembly 100 and generally extends between the proximal and distal ends 208, 210 of the table segment 200. The movement means 240 generally further includes a driver means 270 operatively coupled to the longitudinal translation means 250, where the driver means moves the longitudinal translation means 250 and the locating assembly 100 in the longitudinal direction L_M or L_T .

40 In the particular embodiment illustrated, the driver means 270 includes a motor 272 mounted to the table segment 200 bottom surface 204 and a sprocket 276 rotationally driven by and operatively coupled to the motor 272 (e.g., via a driven shaft 274 as shown). Suitably, the motor 272 and driven sprocket 276 are mounted at the proximal end 208 of the table segment 200 via one or more mounting plates 278 welded or otherwise secured to the bottom surface 204. As further shown, the longitudinal translation means 250 can include an endless chain 252 extending between the proximal and distal ends 208, 210 of the table segment 200 and is operatively connected to the rotationally driven sprocket 276. For example, a freely rotating sprocket 254 can be mounted at the distal end 210 of the table segment 200 via a mounting bracket 256 (e.g., which can be itself mounted to another mounting plate 278) and a pin 255 for rotatably mounting the sprocket 254 to the bracket 256, and the chain 252 can be secured at both ends by the free and driven sprockets 254, 276. Suitably, the mounting bracket 256 is adjustable in the longitudinal direction (e.g., via a bolt as shown in FIG. 12 that can be tightened or loosened) to permit the adjustable selection of the tension in the chain 252 to a desired value so that a revolution counter or servo unit in the motor 272 can be calibrated to control the precise location of the locating assembly 100 along the table segment 200 length during operation. Thus, the mounting block 120 can be mounted to the outside edge of the chain 252 such that rotational motion of the motor 272/shaft 274/driven sprocket 276 results in

longitudinal translational motion of the chain 252 and the locating assembly 100 (e.g., in either direction depending on the direction of rotation). In another embodiment (not shown), the driver means 270 (e.g., motor 272 and driven sprocket 276) could be positioned intermediate the proximal and distal ends of the longitudinal translation means 250/chain 252, for example with a free sprocket anchored to each end of the chain 252 and where the driven sprocket 276 engages the inside edge of the chain 252 as some point intermediate the ends. In some embodiments, a stop 260 (e.g., a rod or plate) can be mounted to a bottom outside edge of the table segment 200 near to the free and/or driven sprockets 254, 276 to prevent the locating assembly 100 from approaching the sprockets during use. As further shown, a chain guard 258 can be mounted to the bottom surface 204 of the table segment 200 such that the guard 258 divides the outside and inside edges of the chain 252 over at least part of the chain's extent and optionally provides a lip portion beneath the chain 252 to limit any undesired sagging of the chain 252 throughout its extended life.

The locating table segment 310 includes at least one movement means 240 and at least one locating assembly 100. In an embodiment, the locating table segment 310 can have only a single locating assembly 100 and a single movement means 240 (e.g., mounted thereto), such that only one side surface 206 of the table segment 200 has an associated locating assembly 100. In the illustrated embodiment of FIG. 8, however, the locating table segment 310 can have (i) a first locating assembly 100A and a first movement means 240A mounted thereto, with the first locating assembly 100A being positioned adjacent a first side surface 206A of the table segment 200, and (ii) a second locating assembly 100B and a second movement means 240B mounted thereto, with the second locating assembly 100B being positioned adjacent a second side surface 206B of the table segment 200 that opposes the first side surface 206A (e.g., in the width direction W_T). For example, as particularly seen in FIG. 8, the first movement means 240A can include a driver means 270 (e.g., including a motor 272 and driven sprocket 276) mounted to the proximal end 208 of the bottom surface 204, while its longitudinal translation means 250 (e.g., chain 252 as seen in FIG. 7) extends along the edge length of the table segment 200 where it is anchored at the distal end 210 (e.g., via a free sprocket 254). Conversely, the second movement means 240B can include another driver means 270 mounted to the distal end 210 of the bottom surface 204, while its longitudinal translation means 250 (e.g., another chain 252) extends along the opposing edge length of the table segment 200 where it is anchored at the proximal end 208 (e.g., via another free sprocket 254).

Truss Assembly System

FIG. 1 illustrates the truss assembly system 300 according to the disclosure and its related method of use. The system 300 generally includes a first table segment (which is a locating table segment 310 according to any of its various embodiments) and a second table segment (which can be an additional locating table segment 310 or a blank table segment 320). The locating assembly 100/mounting block 120, the first table segment 310, and/or the second table segment 310/320 are suitably arranged to be parallel or substantially parallel (e.g., as characterized by the longitudinal direction of each, for example to within a machining tolerance such as not more than 1°, 0.5°, 0.2°, or 0.1°). The first table segment 310 and the second table segment 310/320 are spaced apart to define a slot 330 between adjacent side surfaces 206 of the table segments. The slot 330 has a shape and cross section complementary to that of the second portion 150 of the guide assem-

bly 140. In a general sense, the second portion 150 of the guide assembly 140 freely fits in the slot 330, in particular such that the second width W_2 is not more than the slot 330 width at all relevant points within the slot 330 where the locating assembly 100 is intended to operate/traverse. Suitably, the second width W_2 is substantially the same as the slot 330 width at all relevant points so that locating assembly 100 is stabilized against undesired lateral movement in the width direction W_M as it is positioned at various points along the length of the table segment 200 (e.g., the second width W_2 is the same as or slightly smaller than the slot 330 width to reduce unnecessary friction but to provide the desired lateral stability). Additionally, the slot cross section in the longitudinal direction L_M can be the same as that of the second portion 150 at points thereof adjacent to or in contact with the table segment 200 sidewalls 206 defining the slot 330.

More specifically, the first portion 148 of the guide assembly 140 is below the first and second table segment 310, 320 bottom surfaces 204, for example where a segment such as a lip or flange section of the first portion 148 extends below the table segments 310, 320 and can be in contact with or next to each bottom surface 204, with or without any intervening structure. Similarly, the third portion 152 of the guide assembly 140 is above the first and second table segment 310, 320 top surfaces 202, for example where a segment such as a lip or flange section of the third portion 152 extends above the table segments 310, 320 and can be in contact with or next to each top surface 202, with or without any intervening structure. The second portion 150 of the guide assembly 140 is disposed in the slot 330 and is adjacent the first and second table segment 310, 320 side surfaces 206, for example where all or some of the side surface 146 of the guide assembly 140 second portion 150 is in contact with or next to each side surface 206, with or without any intervening structure. Accordingly, the mounting block 120 is below both the table segment 310, 320 bottom surfaces and the first portion 148 of the guide assembly 140, and the locating block 160 is located above the table segment 310, 320 top surfaces 202 and the third portion 152 of the guide assembly 140.

The truss assembly system 300 suitably includes a plurality of first and second table segments 310, 320 positioned adjacent each other (e.g., in alternating fashion between a first table segment 310 and a second table segment 310, 320). The collective top surfaces 202 of the table segments 310, 320 thus define a top table surface 340 that includes a plurality of slots 330 each having an independently positionable locating assembly 100 therein. The plurality of independently positionable locating assemblies 100 permits the system 300 to define an outline via the blocks 160 corresponding to a potentially large and/or intricate geometric shape of a desired truss 400 to be assembled.

The truss assembly system 300 can further include a computer control system 350 that is operatively connected (e.g., electronically) to any or all of the movement means 240 in the truss assembly system 300. The computer control system 350 allows the particular longitudinal position of each locating assembly in the system 300 to be independently selected by a user, and the control system 350 then interfaces with/controls each movement means 240 to move the locating assemblies 100 to the selected positions. Computer software and hardware (e.g., memory, processor, user interface, electro-mechanical interface) for the control system 350 is conventionally available. In the illustrated embodiments, a revolution counter or servo unit incorporated in the motor 272 is calibrated to control the precise location of the locating assembly 100 insofar as a rotation count of the shaft 274/driven sprocket 276 can be directly correlated to a longitudinal trans-

lational movement of the chain 252 and the locating assembly 100 mounted thereto. In the illustrated chain-and-sprocket embodiment, the absence of any slippage between components of the movement means 240 results in the precise determination and control of the locating assembly 100 longitudinal position. In some embodiments, the movement means 240/control system 350 can include electronic overload protection (e.g., which can monitor the instantaneous electrical current being consumed to drive the movement means 240 as well as terminate the movement means 240 operation if desired, for example when the current exceeds a selected threshold level that could indicate the presence of an obstruction to further locating assembly 100 movement.

In an embodiment, the truss assembly system 300 can further include a motion or proximity sensor 262. The sensor 262 can be mounted in any convenient location in the system 300 so that it is capable of detecting the motion and/or presence of the locating assembly 100 or a component thereof. For example, as illustrated in FIG. 1, the sensor 262 can be mounted on the bottom surface 204 of the table segment 200 so that it extends into the slot 330, such as in the vicinity of the stop 260 and the sprocket 254 or 276. As shown in FIG. 1, a pair of sensors 262 are mounted near opposing side surfaces 206, one at or near the proximal end 208 and one at or near the distal end 210 of the table segment 200 (e.g., where a table segment 200 has one sensor 262 for each movement means 240 mounted thereto). A suitable sensor 262 is an inductive proximity sensor that senses metal (e.g., a metal mounting block 120 or a metal locating block 160 as a component of the locating assembly 100), for example as available from Aotoro (Zhejiang, China). In the illustrated embodiment, the sensor 262 has a line of sight (indicated by arrows) that is aimed along the length of the slot 330 and is vertically positioned so that it detects the presence of a metal mounting block 120 as the locating assembly 100 approaches the stop 260.

The sensor(s) 262 can be operatively connected (e.g., electronically connected) to either or both of the movement means 240 and the computer control system 350. The presence and/or motion of the locating assembly 100 can be detected as the locating assembly 100 approaches the proximal or distal ends 208, 210 of the table segment 200 (e.g., near the stop 260 or sprocket 254/276, such as within about 0.5 cm or 1 cm to about 2 cm or 5 cm of the stop or sprocket). The sensor 262 provides a feedback to the movement means 240/computer control system 350, which in turn signals the driver means 270/motor 272 to substantially reduce the speed of the locating assembly 100. At the substantially reduced speed, the locating assembly 100 can further progress until it impacts the stop 260. The low-speed impact prevents jamming or other disruption of the movement means 240. Further, when the stop 260 is located at a known (e.g., fixed) position along the length of the table segment 200, the impact can be used to accurately calibrate the internal length positioning system of the truss assembly system 300 (e.g., within the computer control system 350). For example, prior to use of the system 300 for truss 400 assembly (e.g., when there are no truss segments 410/420 placed on the table), the locating assembly 100 can be traversed along the length of the table segment 200 until it then experiences the low-speed impact with the stop 260 near the sensor 262 (e.g., in the vicinity of the corresponding driver means 270/motor 272). The known position of the stop 260 permits rapid, precise, automatic calibration of the locating assembly's 100 position along the longitudinal length of the table 200 (e.g., in combination with the revolution counter or servo unit incorporated in the motor 272 as described above).

The particular arrangement of first and second table segments 310, 320 is not particularly limited, and the table segments can be suitably selected such that each desired slot 330 includes a locating assembly 100 (e.g., a single assembly per slot). In an embodiment, each of the first and second table segments 310, 320 can be locating table segments 310. In the context of FIG. 1, this embodiment is represented with the middle and right-most table segments being locating table segments 310, each with a single movement means 240A and a single locating assembly 100A. A blank table segment 320 can be incorporated into the system 300 where no locating assembly 100 is desired (e.g., as in the terminal table segment illustrated by the left-most table segment in FIG. 1). In another embodiment, the first and second table segments 310, 320 can alternate such that the first table segment is a locating table segment and the second table segment is a blank table segment 320. The blank table segment 320 generally has no locating assembly 100 (although it may be coupled with a locating assembly 100 of an adjacent locating table segment 310), for example representing a single table plank/segment that has no movement means 240 or locating assembly 100 mounted thereto. In the context of FIG. 1, this embodiment is represented with the middle table segment being a locating table segment 310 that includes dual movement means 240A/240B and dual locating assemblies 100A/100B on opposing sides of the table segment 200, while the left- and right-most table segments are blank table segments 320.

FIG. 1 further illustrates a method of assembling a construction truss 400 using the truss assembly system 300 (in particular in an embodiment with multiple locating assemblies 100). Each of the locating assemblies 100 in the system 300 is first positioned to correspond to a shape (e.g., outline) of a desired construction truss 400 (e.g., building or roof truss). The truss 400 is generally a planar truss and its shape is not particularly limited. The system 300 can be appropriately sized (e.g., in terms of both physical dimensions and number of locating assemblies 100) to accommodate any desired shape, for example including a triangle, trapezoid, or any other general triangular, rectangular, or polygonal shape, regular or irregular, symmetric or asymmetric. The particular locations of the locating assemblies 100 are generally selected by a user, for example using the computer control system 350 (e.g., where specific locations can be input by the user and/or retrieved from a database of pre-set truss 400 geometries) to activate the movement means 240 and move the assemblies 100. A plurality of truss segments 410 (e.g., pre-cut segments of appropriate size, shape, and length depending on the final truss 400 shape/size) are then placed on the table surface 340 (e.g., manually by a user) in the shape defined by the locating assemblies 100. If desired, interior truss support segments 420 can be positioned within the interior of the shape defined by the locating assemblies 100 (e.g., to provide additional structural support to the eventual truss 400). The truss segments 410, 420 are then fastened together (e.g., manually by a user) to form an assembled truss 400 using any desired fastening means 412 (e.g., nails, nail plates, screws) suitable for the particular truss segment material used. The assembled truss 400 is then removed from the table surface 340, at which time the locating assembly 100 positions can be repositioned for a new truss 400 geometry, or the existing locating assembly 100 positions can be used to construct another truss 400 having the same geometry as the previous truss 400.

Because other modifications and changes varied to fit particular operating requirements and environments will be apparent to those skilled in the art, the disclosure is not considered limited to the examples chosen for purposes of

illustration, and covers all changes and modifications which do not constitute departures from the true spirit and scope of this disclosure.

Accordingly, the foregoing description is given for clarity of understanding only, and no unnecessary limitations should be understood therefrom, as modifications within the scope of the disclosure may be apparent to those having ordinary skill in the art.

Throughout the specification, where the processes, apparatus, or systems are described as including components, steps, or materials, it is contemplated that the processes, apparatus, or systems can also comprise, consist essentially of, or consist of, any combination of the recited components or materials, unless described otherwise. Numerical values and ranges can represent the value/range as stated or an approximate value/range (e.g., modified by the term "about").

25 What is claimed is:

1. A locating assembly comprising: (a) a mounting block having a top surface and defining: (i) a longitudinal direction, (ii) a width direction perpendicular to the longitudinal direction, and (iii) a height direction perpendicular to the longitudinal direction and the width direction; (b) a guide assembly having a bottom surface and an opposing top surface, the guide assembly bottom surface being mounted to the mounting block top surface and extending in the height direction relative to the mounting block, the guide assembly comprising: (i) a first portion having a first width, (ii) a second portion having a second width, and (iii) a third portion having a third width, wherein (A) the first portion is located closer in the height direction to the mounting block top surface than second portion and the third portion, (B) the second portion is located intermediate the first portion and the third portion in the height direction, and (C) the first width and the third width are greater than the second width; (c) optionally a locating block having a bottom surface, the locating block bottom surface being mounted to the guide assembly top surface and extending in the height direction relative to the guide assembly; and (d) optionally (i) a fastening means for fastening the mounting block, the guide assembly, and optionally the locating block together, and (ii) a compression means for exerting a compression force in the height direction between the first portion and the third portion of the guide assembly; and wherein: (i) the mounting block extends in the longitudinal direction; and (ii) the locating assembly further comprises an alignment guide having a bottom surface and an opposing top surface, the alignment guide bottom surface being mounted to the mounting block top surface at a longitudinal position spaced away from the guide assembly and extending in the height direction relative to the mounting block, the alignment guide comprising: (A) a first portion having a first width, and (B) a second portion having a second width, wherein (I) the first portion is located closer in the height direction to the mounting block top surface than second portion, and (II) the first width is greater than the second width.
2. The locating assembly of claim 1, wherein the guide assembly has an I-shaped cross-section in the width direction and the height direction.

19

3. The locating assembly of claim 1, wherein the guide assembly comprises a material having a low coefficient of static friction when in contact with steel.

4. The locating assembly of claim 1, wherein the guide assembly comprises a low-friction polymeric material selected from the group of poly(amides), poly(imides), poly(alkylenes), fluorinated poly(alkylenes), poly(vinyl aromatics), poly(acetals), copolymers thereof, and mixtures thereof.

5. The locating assembly of claim 1, wherein the guide assembly comprises two or more separate portions mounted together.

6. The locating assembly of claim 1, wherein the locating block is present and has a circular cross section in the width direction and the longitudinal direction.

7. The locating assembly of claim 1, wherein the fastening means and the compression means are present and collectively comprise a bolt extending in the height direction through the mounting block, the guide assembly, and optionally the locating block when present.

8. A locating table segment comprising: (a) a table segment having (i) a top surface, (ii) an opposing bottom surface and (iii) a side surface intermediate the top surface and the bottom surface, and defining (i) a longitudinal direction, (ii) a width direction perpendicular to the longitudinal direction, and (iii) a height direction perpendicular to the longitudinal direction and the width direction; (b) the locating assembly of claim 1 positioned adjacent the table segment side surface, wherein: (i) the longitudinal direction of the locating assembly mounting block and the longitudinal direction of the table segment are substantially parallel; (ii) the first portion of the guide assembly is below the table segment bottom surface; (iii) the second portion of the guide assembly is adjacent the table segment side surface; (iv) the third portion of the guide assembly is above the table segment top surface; (v) the mounting block is below the table segment bottom surface; and (vi) the locating block, when present, is located above the table segment top surface; and (c) a movement means for moving the locating assembly in the longitudinal direction, wherein (i) the movement means is mounted to the locating assembly, and (ii) the movement means is positioned below the table segment bottom surface.

9. The locating table segment of claim 8, wherein the first portion and the third portion of the locating assembly guide assembly maintain the locating assembly in a fixed position in the height direction relative to the table segment.

10. The locating table segment of claim 9, wherein the first portion and the third portion exert a compressive force between the top surface and the bottom surface of the table segment.

11. The locating table segment of claim 8, wherein the movement means comprises: (i) a longitudinal translation means for moving the locating assembly in the longitudinal direction, the longitudinal translation means being mounted to the mounting block of the locating assembly and extending between proximal and distal ends of the table segment; and (ii) a driver means operatively coupled to the longitudinal translation means for moving the longitudinal translation means and the locating assembly in the longitudinal direction.

12. The locating table segment of claim 11, wherein: (i) the driver means comprises (A) a motor mounted to the table segment bottom surface, and (B) a sprocket rotationally driven by and operatively coupled to the motor; and (ii) the longitudinal translation means comprises an endless chain extending between the proximal and distal ends of the table and being operatively connected to the rotationally driven sprocket.

20

13. The locating table segment of claim 8, wherein the locating table segment has a single locating assembly and a single movement means mounted thereto.

14. The locating table segment of claim 8, wherein the locating table segment has (i) a first locating assembly and a first movement means mounted thereto, with the first locating assembly being positioned adjacent a first side surface of the table segment, and (ii) a second locating assembly and a second movement means mounted thereto, with the second locating assembly being positioned adjacent a second side surface of the table segment, the second side surface opposing the first side surface.

15. A truss assembly system comprising: (a) a first table segment comprising a locating table segment comprising: (i) a table segment having (A) a top surface, (B) an opposing bottom surface and (C) a side surface intermediate the top surface and the bottom surface, and defining (A) a longitudinal direction, (B) a width direction perpendicular to the longitudinal direction, and (C) a height direction perpendicular to the longitudinal direction and the width direction; (ii) the locating assembly of claim 1 positioned adjacent the table segment side surface, wherein: (A) the longitudinal direction of the locating assembly mounting block and the longitudinal direction of the table segment are substantially parallel; (B) the first portion of the guide assembly is below the table segment bottom surface; (C) the second portion of the guide assembly is adjacent the table segment side surface; (D) the third portion of the guide assembly is above the table segment top surface; (E) the mounting block is below the table segment bottom surface; and (F) the locating block, when present, is located above the table segment top surface; and (iii) a movement means for moving the locating assembly in the longitudinal direction, wherein (A) the movement means is mounted to the locating assembly, and (B) the movement means is positioned below the table segment bottom surface; (b) a second table segment having (i) a top surface, (ii) an opposing bottom surface and (iii) a side surface intermediate the top surface and the bottom surface, and defining (i) a longitudinal direction, (ii) a width direction perpendicular to the longitudinal direction, and (iii) a height direction perpendicular to the longitudinal direction and the width direction; wherein: (i) the longitudinal direction of the locating assembly mounting block, the first table segment, and the second table segment are substantially parallel, (ii) the first table segment and the second table segment are spaced apart to define a slot between adjacent side surfaces thereof, the slot having a shape and cross section complementary to that of the second portion of the locating assembly guide assembly; (iii) the first portion of the guide assembly is below the first and second table segment bottom surfaces; (iv) the second portion of the guide assembly is disposed in the slot and adjacent the first and second table segment side surfaces; (v) the third portion of the guide assembly is above the first and second table segment top surfaces; (vi) the mounting block is below the first and second table segment bottom surfaces and the first portion of the guide assembly; and (vii) the locating block, when present, is located above the first and second table segment top surfaces.

16. The truss assembly system of claim 15, wherein the system comprises a plurality of first and second table segments positioned adjacent each other, thereby defining a table surface comprising a plurality of slots each having an independently positionable locating assembly therein.

17. The truss assembly system of claim 15, wherein: (i) the first table segment has a single locating assembly mounted thereto; and (ii) the second table segment has a single locating

assembly mounted thereto, the locating assembly comprising the same components as those of the first table segment.

18. The truss assembly system of claim **15**, wherein: (i) the first table segment has first and second locating assemblies mounted at opposing ends and sides of the first table segment; 5 and (ii) the second table segment is a blank table segment having no movement means.

19. A method for assembling a truss, the method comprising: (a) providing the truss assembly system of claim **16**; (b) 10 positioning each of the locating assemblies to correspond to a shape of a construction truss; (c) positioning (i) a plurality of truss segments on the table surface in the shape defined in (b), and (ii) optionally one or more interior truss support segments within the interior of the shape defined in (b); and (d) fastening the plurality of truss segments and any truss support 15 segments together to form an assembled truss.
